UNITED STATES PATENT OFFICE.

JOHN THOMAS RHAMSTINE, OF DETROIT, MICHIGAN.

ELECTRIC SWITCH.

Application filed February 5, 1920. Serial No. 356,520.

To all whom it may concern:

Be it known that I, JOHN THOMAS RHAMSTINE, a citizen of the United States, residing at Detroit, in the county of Wayne and State of Michigan, have invented a new and useful Improvement in Electric Switches, of which the following is a specification.

The present invention relates to electric switches, and particularly to those of the 10 type controlled by timing mechanism.

An object is to provide a time controlled switch which may be easily set; which is of relatively small compact form; which comprises relatively few movable parts; which 15 is designed to maintain a circuit closed for a desired period of time; and which positively breaks the circuit and maintains the same open upon the termination of the time period for which the switch may be set.

Another object of the invention is to provide a time controlled switch which may be cheaply and easily manufactured; which may be made rapidly and in large numbers; and which may be installed as a part of 20 25 small electrical devices where current is desired for predetermined periods of time, such as in cooking appliances, namely, toasters and the like.

The above, and various other objects and 30 advantages of this invention will in part be described in, and in part be understood from, the following detailed description of the present preferred embodiment, the same being illustrated in the accompanying drawing, wherein;

Fig. 1 is a side elevation partly in section of a time controlled switch constructed according to the present invention.

Fig. 2 is a face view thereof.

Fig. 3 is a detail underside perspective view of the contact disc of the device, and

Fig. 4 is a detail perspective view of the pivoted contact arm and its mounting.

Referring to the drawing by numerals, 10 45 designates a casing which may be cylindrical in form and of any desired depth, the same having a bottom 11 and a rotatable top or cap 12.

A plate or partition 13 is arranged in the 50 casing in spaced relation to the bottom 11 and divides the casing into upper and lower compartments. A suitable turning mechanism 14, of preferably the spring actuated type as shown, is mounted in the lower compartment of the casing 10 and is supported upon a plate or false bottom 15 secured in

the casing near the bottom 11. This turning mechanism has an arbor or shaft 16 which rises through the partition 13 and extends upwardly through the cap 12. The cap 12 60 turns with and may be detachably mounted on the arbor 16 by a nut 17, or the like, admitting removal of the cap 12 and access to the casing for cleansing, adjustment of the parts, and the like.

Fixed upon the arbor 16 in the upper compartment is a disc 18 forming one contact in a circuit from wire 19 through the timing mechanism 14 and the arbor 16. The contact disc 18 carries on its under side 70 a circuit breaking or insulating block 20 arranged near the outer edge of the disc and having beveled or cam ends for a purpose which will hereinafter appear.

The timing mechanism 14 urges the arbor 75 16 to turn in one direction, such as in an anti-clockwise direction, and the disc 18 carries a movable stop 21 adapted to engage a fixed stop 22 carried by the casing 10 and projecting into the path of the movable 80 stop 21. The stop 22 may be in the form of a screw passing through a reinforced side of the casing 10 and which detachably holds a fixed pointer 23 on the upper end of the casing. The pointer overhangs the edge of 85 the cap 12, and the latter has a dial 24 divided into consecutively numbered time intervals, such as minutes, beginning and ending at a zero point 25. The movable stop 21 is so positioned on the contact disc 18 as to 90 engage the fixed stop 22 when the zero point 25 registers with the pointer 23.

The partition 13 carries an upstanding bracket arm 26 seated upon an insulating strip 27 and connected to the other wire 95 28 of the circuit. The wire 28 may pass up through the bottom 11, plate 15 and partition 13, and is insulated therefrom by a covering 29 of rubber or the like. The wire 19 may be secured directly to the casing 100 near the bottom as shown, or the current may be conducted to the contact disc in any other suitable manner.

Pivoted at one end on the bracket arm 26 is a movable contact arm 30 adapted to 105 extend toward the contact disc 18 and urged thereagainst by a spring 31 which is seated on a block 32 secured to the partition 13. The block 32 has a spring seating face inclined to support the spring 31 substantially at right angles to and beneath the pivoted contact arm 30. The free end of

the arm 30 is curved downward to form a shoe or sliding surface adapted to bear against the lower side of the contact disc 18.

The timing mechanism 14 normally holds the stops 21 and 22 in engagement with each other and the zero point 25 in register with the pointer 23. In this normal position of rest, the insulating block 20 lies between the disc 18 and the arm 30 to break and hold 10 open the circuit.

To operate, the edge of the cap 12, which may be milled or roughened as shown, is grasped between the fingers and turned clockwise until the desired time indication 15 on the dial 24 registers with the pointer 23. This turning of the cap 12 in a clockwise direction also winds the spring of the timing mechanism 14 to put it into condition for subsequent operation. The turning of the 20 cap 12 by hand also rotates the disc contact 18 and moves the insulating block 20 from between the disc 18 and the contact finger 30, which latter is urged against the disc 18 by the spring 31 and completes the circuit.

25 Current now flows through the circuit, and as soon as the cap 12 is released from the hand the timing mechanism turns the arbor 16 and the parts carried thereby anti-clockwise until the stops 21 and 22 come together, 30 during all which time the circuit is closed. As the stops 21 and 22 come together the disc 18 brings the block 20 against the pivoted arm 30 and moves the latter away from the disc; thus breaking the circuit as the parts 35 come to rest. Of course the timing mechanism, is retarded in its operation proportionately to the character of the period of time divisions on the dial 24, so that should the cap 12 be set at "5" it would take a period of 40 time equal to five times the period of time designated between the graduations for the cap 12 to return to rest and break the circuit.

The switch, therefore, normally maintains the circuit open, and can be optionally adjusted to keep the circuit closed various 45 lengths of time for different uses and conditions met with in the use of the switch.

It is of course understood that various 50 modifications and changes may be made in the details of construction and design of the

above specifically described embodiment of this invention without departing from the spirit thereof, the changes and modifications being restricted only by the scope of the following claims.

55

What is claimed is:—

1. An electric switch comprising a casing, a clock mechanism mounted in the bottom of the casing and having main arbor disposed coaxially in the casing, a cap for the casing 60 fixed to the arbor for movement by the clock mechanism and for rewinding the same, a contact disc mounted on the arbor in the upper part of the casing adapted to turn with the arbor, a stationary contact mounted in the upper part of the casing and normally urged against the contact disc for completing a circuit therethrough, and an insulating member carried by the disc to travel therewith and arranged in the path of the stationary contact for spacing the same from the disc when the latter is in its normal position of rest.

2. In an electric switch, a casing, an arbor coaxial in the casing, a clock mechanism 75 connected to the arbor for urging the same to turn in one direction, a cap for the casing fixed upon the arbor adapted to turn therewith in one direction for operation of the switch and adapted to be turned in the 80 opposite direction for rewinding the clock mechanism, a disc mounted on the arbor in the upper part of the casing, a stationary contact in the casing normally urged toward the disc for closing a circuit therethrough, 85 cooperating stops on the disc and casing for determining a position of rest of the disc and clock mechanism, an indicator carried by the casing and arranged to coact with the cap for indicating the extent of rewinding 90 of the clock mechanism and the turning of the disc out of its normal position of rest, and an insulating block carried by the disc in position to engage the stationary contact 95 spaced the same from the disc when the latter is in its position of rest.

In witness whereof I hereunto set my hand.

JOHN THOMAS RHAMSTINE.
